CLEANING APPARATUS

Gene Brenfleck, St. Louis, Mo.

Application January 24, 1955, Serial No. 483,611

4 Claims. (Cl. 134—182)

This invention relates to a fluid motor and agitator adapted to be mounted in a container for cleaning articles with an agitated liquid, and more particularly, to a cleaning apparatus which filling station and garage men can use for quickly, thoroughly, and safely cleaning automotive parts with a highly volatile cleaning solvent or fluid.

At present, automotive repair men clean automotive parts such as carburetor parts, fuel pumps, gears, piston rings, valves, air filters, etc. in various ways, including hand rubbing them with gasoline, coal oil, kerosene or other cleaning fluids. Various washers with agitators therein have been designed, but are powered with relatively expensive electric motors or with hydraulic motors which require large quantities of water and water tight hose connections. These motors have been mounted beneath the container with their rotatable shafts extending centrally and axially upwardly through the bottom of the cleaning container. This arrangement requires a relatively large space or volume for the agitator, a gasket or seal to prevent the leakage of cleaning fluid through the bottom, and results in accumulation of foreign matter on the agitator itself. In devices where the agitator has been driven by an air motor, the air has been expelled into the cleaning chamber or mixed with the gasoline or other cleaning fluid therein, thereby causing excessive evaporation and producing dangerous conditions for the operator because of the fumes and highly inflammable vapors.

One of the principal objects of the present invention is to provide a relatively simple fluid motor and agitator which can be secured to a cleaning container for agitating a cleaning fluid therein and directing said fluid against and around articles to be cleaned.

Another object is to provide an air motor in a cleaning container wherein the air is expelled immediately from the air motor and is not permitted to enter the cleaning chamber or to contact or mix with the cleaning fluid therein.

Another object is to provide a relatively small fluid motor and agitator which is simple and inexpensive to make and which can be easily attached to a cylindrical drum of the type which is normally found in a filling station or garage.

Still another object is to provide a fluid motor and agitator which has only a few simple parts and occupies only a small part of the entire volume and cross sectional area of the cleaning container to which it is attached.

Another object is to provide a tubular agitator having a deflector which directs the agitated cleaning fluid against the parts to be cleaned and into a basket or parts holding member which also deflects and directs the agitated liquid over and through said parts. Another object is to position the agitator so that foreign matter will not accumulate thereon.

These and other objects and advantages will become apparent hereinafter.

2

The present invention is embodied in a fluid motor and agitator adapted to be mounted along the wall of a container for agitating cleaning fluid therein without allowing the cleaning fluid and propelling fluid to mix.

5 The invention is also embodied in the cleaning apparatus including said fluid motor and agitator, a container, and a parts carrying means positioned therein.

The invention also consists in the parts and in the arrangements and combinations of parts hereinafter described and claimed. In the accompanying drawings which form part of this specification and wherein like numerals and like symbols refer to like parts wherever they occur:

Fig. 1 is an exterior perspective view of the cleaning container with its cylindrical wall broken to show a side view of the fluid motor and agitator.

Fig. 2 is a horizontal cross-sectional view of the device taken along the line 2—2 of Fig. 1.

Fig. 3 is a perspective view of the parts carrying basket, 20 Fig. 4 is a perspective view of the fluid motor and agitator assembly,

Fig. 5 is an enlarged cross-sectional view taken along the line 5—5 of Fig. 1,

Fig. 6 is a vertical cross sectional view of the fluid 25 motor and agitator assembly taken along the lines 6—6 of Fig. 4, and

Fig. 7 is a horizontal cross sectional view taken along the line 7—7 of Fig. 6.

Referring now to the drawings in detail, it will be seen that the embodiment of the invention which has been illustrated comprises a fluid motor and agitator assembly A fixedly secured to the upper portion of a cleaning container C having a parts carrying basket B removably positioned therein.

35 The cleaning container C is leakproof and comprises a circular bottom member 1 with an upstanding cylindrical shell or wall 2 having a cover 3 hingedly or removably secured thereto. A handle 4 is provided for removing or opening said cover 3 and for sealably closing said cover 3 on the cleaning container C so that no cleaning fluid can escape therefrom. The cleaning container C is also provided with carrying handles 5 mounted on opposite sides thereof.

40 A fluid motor and agitator assembly A is secured to the upper inner portion of the wall 2 of the cleaning container C, preferably between said handles 5, by means of bolts 6 with a gasket or seal 7 therebetween and washers 8. An air intake tube 9 having a control valve 10 therein extends outwardly from the container C opposite to the upper portion of the fluid motor and agitator assembly A. The container C is provided with an air exhaust port 11 adjacent to said air intake tube 9.

45 The fluid motor and agitator assembly A comprises a motor 12 having an agitator 13 depending vertically therefrom. The motor 12 comprises a relatively flat base plate 14 having a depending circular flange 15 thereon. A relatively thick motor cover 16 is sealably secured to said base plate 14 by means of screws or bolts 17, said cover 16 having a top portion 18 and downwardly extending side walls 19. The side walls 19 are provided with holes for receiving said bolts 6. One side edge 20 of said motor 12 is curved to fit the contour of the cleaning container C. The motor cover 16 and base plate 14 form a motor chamber 21 which connects with the air intake tube 9 and exhaust port 11, but which does not connect with the inside of said container C. A rotor 22 having a smooth flat bottom 23 and a plurality of buckets or plates 24 thereon is rotatably mounted in said motor chamber 21. A rotatable shaft 25 is fixed to

50 said rotor 22 and extends downwardly through a hole 26 in the motor base plate 14. Each blade 24 has a fluid impinging surface 27 and a rearward surface 28, said

surfaces being arranged so that a source of air under pressure directed into the air intake tube 9 will strike the forward surface 27 and cause the rotor 22 to rotate in the direction of the arrows, said air being immediately exhausted to the atmosphere through the exhaust port 11 without entering the container proper.

The agitator 13 comprises a hollow vertically positioned cylindrical tube 29 secured to said flange 15 by means of a collar 30 and fastening means 31. The tube 29 has a substantially horizontal lower bracket 32 thereon with a hole 33 therein for receiving the bottom portion of said rotatable shaft 25 for holding it in vertical alignment. The upper portion of said tube 29 is provided with a substantially horizontal slot 34 opposite which a starter wheel 35 having a knurled surface 36 is secured to said shaft 25 for starting the fluid motor 12 in the event that the initial blast of incoming fluid or air under pressure does not turn the rotor 22 in the fluid motor 12. The bottom portion of the tube 29 is provided with a deflector 37 formed by a vertical cut 38 and a horizontal cut 39 therein. The deflector 37 is bent outwardly from the tube 29 to a predetermined position, explained hereinafter. The rotatable shaft 25 is provided with a plurality of fins 40 fixedly secured thereto opposite to said deflector 37 for agitating a cleaning fluid or solvent into which said fins 40 are immersed. The tube 29 forms an agitator chamber 41 therein.

The parts carrying basket B, shown in Fig. 3, comprises a substantially circular wire mesh bottom 42 having a cut off portion 43. The basket B is provided with a curved side wall or deflector 44 which has an opening 45 above said cut off portion 43, said opening 45 being covered with a plurality of bars 46 or wire mesh for preventing the automotive parts to be cleaned from falling out of said basket B. The basket B is provided with a plurality of legs 47 for supporting the parts in an elevated position from the bottom 1 of the container C and a lifting handle 48 for removing and inserting said basket B into the container. The cut-off portion 43 is of sufficient size to permit the basket B to be raised and lowered in the container C without contacting the fluid motor and agitator assembly A. The bottom 42 of the basket B defines a sludge chamber 49 therebelow and a cleaning chamber 50 thereabove opposite to said agitation chamber 50.

In operation, a garage mechanic or operator places the dirty automotive parts which might contain grease, oil, carbon, or other foreign matter into the basket B and lowers said basket B into the container C after properly orienting the cut-off portion 43 with respect to the fluid motor and agitator assembly A. The operator then pours in a suitable amount of a special high volatile cleaning solvent which cleans faster than gasoline or the like. The top level of the solvent is preferably kept slightly below the slot 34 opposite to the starting wheel 35. About five gallons of fluid gives good results in a six gallon container. The cover 3 is placed over the container C in tight sealing relation so that the cleaning fluid will not escape. A conduit or hose, which is connected to a source of compressed air or other suitable fluid under pressure, is placed over the air intake tube 9 and the valve 10 is opened thereby starting the motor 12. If the air motor 12 should not start for some reason, such as foreign matter causing it to stick temporarily, the cover 3 is removed and the operator rotates the starter wheel 35 with his finger to start rotation of the rotor 22. The rotation of the rotor 22 causes the submerged fins 40 to rotate, thereby agitating or moving the cleaning solvent from the agitator chamber 41 outwardly from the cylindrical tube 29 in a direction determined by the position of said deflector 37, which is positioned directly opposite to the opening 45 in the parts carrying basket B so that fluid is directed into said basket B against the parts to be cleaned. The curved side wall 44 of the basket

B also acts as a deflector for redirecting the agitated fluid against the automotive parts from a different direction.

The space above the bottom 42 of said basket B forms a cleaning chamber 50 for cleaning the parts. The foreign matter removed from the parts in the cleaning chamber 50 falls through the wire mesh bottom 42 and into a sludge chamber 49 positioned below said bottom 42.

After a predetermined time, the air supply is cut off by closing the valve 10 or removing the air hose, not shown. The cover 3 is removed and the basket B is lifted out of the container C through relatively clean solvent, the foreign matter having dropped into the sludge chamber 49. After one or several loads, the operator can tip the container C to pour out and save most of the cleaning solvent. The solvent still remaining in the bottom of the sludge chamber 49 can be discarded thereby taking most of the foreign matter with it, and the inner cylindrical wall 2 and bottom 1 of the container C can be further cleaned with gasoline or solvent if desired.

The air which enters the air motor 12 to impart rotation to the rotor 22 is immediately expelled from the motor chamber 21 to the atmosphere through the exhaust port 11 and does not enter the cleaning chamber 50 or sludge chamber 49. This prevents evaporation of the highly volatile cleaning solvent and further prevents what might otherwise be a dangerous condition for the operator because of noxious and highly inflammable fumes. The rotor 22 has a relatively smooth bottom portion 23 which bears against a relatively smooth upper surface on the base plate 14 so that the starter wheel 35 is seldom used. However, if the motor 12 does not immediately start when a source of air is directed against the rotor 22, then a slight movement of the starter wheel 35 will free the rotor 22 and cause it to rotate.

This invention is intended to cover all changes and modifications of the example of the invention herein chosen for purposes of the disclosure, which do not constitute departures from the spirit and scope of the invention.

What I claim is:

1. A cleaning apparatus comprising a container adapted to hold a cleaning fluid, a fluid propelled motor and agitator positioned along an inner wall of said container, a parts carrying basket removably positioned in said container opposite to said agitator, said basket having a parts supporting surface with holes therein forming a sludge chamber therebelow in said container and a cleaning chamber thereabove in said container, said fluid propelled motor being sealed from said chambers thereby preventing propelling fluid from entering said chambers, and a deflector positioned opposite to said agitator for directing agitated fluid into said parts carrying basket.

2. A cleaning apparatus comprising a container adapted to hold a cleaning fluid, an air propelled motor and agitator positioned along an inner wall of said container, a parts carrying basket removably positioned in said container opposite to said agitator, said basket having a parts supporting surface with holes therein forming a sludge chamber therebelow in said container and a cleaning chamber thereabove in said container, said air propelled motor being sealed from said chambers thereby preventing propelling air from entering said chambers or mixing with said cleaning fluid, and a deflector positioned opposite to said agitator for directing agitated fluid into said parts carrying basket.

3. A cleaning apparatus comprising a container, a parts carrying member positioned within said container and adapted to be removed therefrom, said member having a parts supporting surface with openings therein and a side wall with an opening therein, an air motor mounted on the inner wall of said container, inlet and outlet means in said wall for supplying and exhausting air under pressure to and from said motor, an agitator positioned in vertical alignment with said motor substantially opposite

to said parts carrying member, said motor adapted to actuate said agitator for agitating a fluid in said container around parts to be cleaned in said parts carrying member.

4. A cleaning apparatus comprising a leakproof container with a cover adapted to be opened, a parts carrying member positioned within said container and adapted to be removed therefrom, said member having a parts supporting surface with openings therein and a side wall with an opening therein, an air motor mounted on the inner wall of said container, inlet and outlet means in said wall for supplying and directly exhausting air under pressure to and from said motor, an agitator positioned beneath said motor substantially opposite to the opening in the side wall of said parts carrying member, said motor adapted to rotate said agitator for directing a fluid in 15 said container around parts to be cleaned in said parts carrying member.
